UNITED STATES PATENT OFFICE.

EDWARD ADAMSON, OF PROVIDENCE, RHODE ISLAND.

REED FOR LOOMS.

SPECIFICATION forming part of Letters Patent No. 223,974, dated February 3, 1880.

Application filed April 24, 1879.

To all whom it may concern:

Be it known that I, EDWARD ADAMSON, of Providence, in the State of Rhode Island, have invented certain new and useful Improvements in Reeds for Looms; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in reeds for weavers' use; and it consists of a reed provided with double springs arranged to telescope one within the other, in combination with dents and means for holding the same, all as will be hereinafter more fully described, and pointed out in the claims.

20 In my drawings, Figure 1 is an elevation of my improved reed with one of the tubes broken away to show the coils and dents in their relations to each other. Fig. 2 is a transverse section on line xx of Fig. 1.

25 Similar reference-letters indicate like parts in all of the figures.

Referring to the drawings, $a a$ are the metal dents, without slots or any extra finish at their ends. $b b'$ are wire coils capable of expansion and contraction, which hold the ends of the dents $a a$ in fixed positions.

30 $A A$ are open tubes, which form casings to the coils $b b'$ and assist in keeping said dents in position against lateral movement.

35 On either end of the reed are bars $c c$, provided with cylindrical ends $d d$, adapted to slide into the open cylinders $A A$ and fit against the coils $b b'$. The purpose of these bars is twofold: first, to hold the dents $a a$ in given positions in relation to each other within the coils, and, secondly, to fill up the spaces outside of the dents and form guards to prevent the shuttle from jumping from its race through the said spaces when the said dents 40 are properly adjusted to suit the warp.

45 At the ends of the tubes $A A$, next to the

cylindrical ends $d d$ of the bars $c c$, small linchpins or other simple mechanical appliances are to be provided, to prevent the bars $c c$ from yielding to the pressure of the coiled springs 50 incased within the tubes. The bars $c c$ may be of any number or size consistent with utility, and are readily adjustable in increasing or diminishing the number per inch of dents and spaces in the reed. The bars c may be of 55 metal or any suitable material.

This arrangement of a coil within a coil is simple and compact, doing away with the necessity of slots in the dents, which are essential when bars are used with interlacing coils, 60 as shown in a patent granted to me of recent date, No. 212,120.

The tubes which incase the coils are about the size of the ordinary reed-ribs, and when in place the edges of the tubes forming their 65 openings bear against the edges of the dents, to prevent, as before mentioned, said dents from moving laterally within the grasp of said coils.

By the use of open tubes in combination 70 with telescoping coils I effect a simple construction to my reed much to its advantage, gaining thereby protection to the springs and stiffness to its general construction.

Having thus described my invention, what 75 I claim as new, and desire to secure by Letters Patent, is—

1. In a weaver's reed, the double springs $b b'$, arranged to telescope the one within the other, in combination with the dents $a a$ and means, 80 substantially as described, for holding the same, as and for the purpose set forth.

2. In combination with the double coil-springs $b b'$, one within the other, and dents $a a$, the open tubes $A A$, as specified. 85

In testimony that I claim the foregoing as my own I affix my signature in presence of two witnesses.

EDWARD ADAMSON.
